UNITED STATES PATENT OFFICE.

JOHN NALESNIK, OF NEW YORK, N. Y.

COMBINED RECEPTACLE AND TABLE.

Application filed January 10, 1928. Serial No. 245,830.

This invention relates to improvements in combined receptacles and tables, and has for one of its objects to provide a receptacle, such as a suitcase, with an improved table attachment connected to the body of the receptacle in such manner that the attachment may be folded and recessed within a portion of said body and extended to an operative position above the receptacle with the latter forming a supporting base for the table top.

Another object is to form the table top of a plurality of foldable sections one of which is hingedly connected to the body of a receptacle and adapted to be braced thereby to retain the top in an extended position, and the connection of said top to the receptacle being such that when the top is folded it may be adjusted and held in a position wherein it will constitute an outer side wall of the receptacle.

The above and other objects will appear more clearly from the following detail description, when taken in connection with the accompanying drawings, which illustrate a preferred embodiment of the inventive idea.

In the drawings—

Figure 1 is a perspective view of the combined receptacle and table in operative position and constructed in accordance with the invention;

Figure 2 is a side elevation showing the table top in its folded position and forming a side wall of the receptacle;

Figure 3 is a detail sectional view illustrating the manner of holding the table top in its folded position, as shown in Figure 2;

Figure 4 is an end elevation with the receptacle in section, showing the table top in its extended or operative position;

Figure 5 is a fragmentary bottom plan of one portion of the table top;

Figure 6 is a similar view of another portion of the table top; and

Figure 7 is an enlarged fragmentary top plan view of the supporting means for the table top with the latter removed.

Referring more particularly to the accompanying drawing, the numeral 10 indicates generally a receptacle which is preferably in the form of a suitcase having the usual hinged cover 11 and a permanent side wall 12 recessed slightly within the body by the extensions 13 of the end walls of the receptacle, said extensions combining to form a recess into which the table top, later to be described, may be adjusted when the same is

in folded position. The wall 12 may be provided with pockets 14 for the reception of various articles such as napkins, eating utensils and the like.

The table top of the present invention comprises a central section 15 and two end sections 16 and 17 forming a continuation of the central section and hingedly connected thereto so that each end section may be folded over upon the central section to assume the position shown in full lines in Figure 2 and in dotted lines in Figure 4. When the sections are folded, as shown in Figure 2, the same constitute, in effect, an outer side wall of the suitcase and are held in position by means of latches 18 pivoted to the ends of the section 16 adjacent the meeting edge of the section 17, said latches engaging both the section 17 and the end walls of the receptacle. To further aid in securing the table top in its folded position the inner edge of the section 16 is provided with a central flap 19 and two end flaps 20, the central flap having a catch 21 adapted to engage a lock 22 carried by the top of the suitcase, while the flaps 20 are provided with studs 23 engageable with catches 24 also carried by the top of the suitcase.

To support the table top in an extended position above the receptacle there are provided three links 25 each having one end pivotally connected at 26 to the top of the receptacle, while the other end of each link is pivotally mounted at 27 to the underside of the central section 15. Adjacent each end of the latter section the same has pivotally connected to its underside one end of a main brace 28, the opposite end of which is provided with an opening for receiving a projection 29 carried by a plate 30' mounted upon the top edge of the cover 11. A further brace 30 is associated with each of the main braces 28 and said brace 30 is likewise pivoted to the bottom of the section 15 at 31 and has its other or free end formed with a hook adapted to engage a stud 32 on the brace 28 intermediate the ends of the latter. With the parts in the position just described, the table top is supported and braced in a position above the receptacle 10 which then forms a base for said top and the sections 16 and 17 may then be adjusted to extended positions in a plane with the section 15. To support said sections 16 and 17 in this position latches 33 are provided which are pivoted to the underside of the section 15 adja-

cent its longitudinal edges and which are capable of being swung to straddle the meeting edges of the section 15 and the end sections 16 and 17 and engage studs 33 on the 5 underside of the latter sections.

To adjust the table top to its folded position, as shown in Figure 2, the braces 30 are first disengaged from the braces 28 and the latter are then disconnected from the projections 29, both the braces 28 and 30 being then swung upwardly against the bottom of the section 15. The sections 16 and 17 are then folded over upon said section 15 and the entire table top is then swung about the 10 pivotal points 26 until the sections 15, 16 and 17 have been recessed between the extensions 13 of the end walls of the receptacle, it being understood that said sections can be moved to a vertical position between said 15 end walls by reason of the pivotal connections of the links 25 with the bottom of the section 15. The flaps 19 and 20 are then engaged with their associated catches and the latches 18 swung to locking position, whereupon the table top will be secured in its folded 20 position.

What is claimed is:

1. A combined receptacle and table including a receptacle body having a recess formed in one side thereof, a table top including a plurality of sections foldable into position within said recess, pivotal connections between said body and said table top whereby the latter may be swung from its folded position to an extended position above said receptacle, and braces carried by one of the sections of said table top and engageable with the receptacle and with each other to support the table top in its extended position.
2. A combined receptacle and table including a receptacle body having a recess

formed in one side thereof, a table top including a plurality of sections foldable into position within said recess, pivotal connections between said body and said table top whereby the latter may be swung from its folded position to an extended position above said receptacle, projecting pins carried by said body, braces pivoted to one of the sections of said table top and engageable with said projecting pins when the top is in extended position, and other braces carried by said section of the table top and engageable with the first named braces.

3. A combined receptacle and table including a receptacle body having a recess formed in one side thereof, a table top including a plurality of sections foldable into position within said recess, links pivotally connecting one of the sections of said table top with said body, braces pivoted to said section of the top and engageable with said body, other braces pivoted to said section and engageable with the first named braces, securing flaps carried by one of the other sections of said table top and engageable with said body to maintain the table top in folded position, and latches carried by one of the sections of the top and engageable with the other section and with said body when said sections are in folded positions.

4. A combined receptacle and table including a receptacle body, a table top, pivotal connections between said body and said table top whereby the latter may be swung from an inoperative position to an extended position above said receptacle, and braces carried by said table top and engageable with the receptacle and with each other to support the table top in its extended position.

In testimony whereof I have affixed my signature.

JOHN NALESNIK.
